AUTOMATIC DEFROSTING SWITCH

Charles Christian Hundemer, Baton Rouge, La.

Application November 10, 1931, Serial No. 574,211

5 Claims. (Cl. 62—115)

My invention relates to the art of mechanical refrigeration and particularly to those refrigerators which employ a so-called chiller that is located within the box or chamber to be cooled. 5 These chillers after a time become covered with frost and as the frost increases in thickness the efficiency of the machine falls off, making it necessary to stop the operation of the machine at intervals in order to defrost the chiller.

10 My present invention primarily has for its object to provide thermostatically controlled means for stopping the action of the chilling mechanism when the chiller has been covered with frost to a predetermined depth and automatically to restore the chiller to action as soon as the defrosting has been completed.

Further, it is an object to provide means for opening and closing the circuit that actuates the motors of electric refrigerators or to open and 20 close the valve that controls the energy or fuel supply for gas refrigerators, as for example, the Electrolux.

Further, the invention has for an object to provide a simple, inexpensive attachment to refrigerators which can be manufactured at low cost and which can be attached to the refrigerators without having to alter their construction. 25

Other objects will in part be obvious and in part be pointed out hereinafter. 30 To the attainment of the aforesaid objects and ends, the invention still further resides in the novel details of construction, combination and arrangement of parts, all of which will be first fully described in the following detailed description, then be pointed out in the appended claims, reference being had to the accompanying drawings, in which:—

Figure 1 is an elevation and part diagrammatic view illustrating my invention in use, defrosting taking place.

Figure 2 is a view similar to Figure 1 showing the position of the parts after defrosting has been completed.

Figure 3 is a vertical longitudinal section substantially on the line 3—3 of Figure 4 of the operating mechanism of the invention as connected for operating a valve.

Figure 4 is a plan view of the invention.

Figure 5 is a diagrammatic view of a refrigerating system showing how my defrosting switch is connected therein.

In the drawings in which like numerals of reference indicate like parts in all of the figures, 1 represents the chiller, 2 the frost, 3 a thermos bulb located in contact with the wall of the chiller

and 4 a thermos bulb spaced from the wall of the chiller a predetermined distance depending upon what thickness of frost it is desired to let accumulate before beginning the defrosting operation.

5 5 is a base of suitable form and structure on which is mounted the controller which governs the action of the chiller. This controller may be either a switch in the electric motor circuit of electrically driven refrigerators, or a valve in the energy or fuel supply line of refrigerators of the gas type. In the following description and in the claims where I refer to a controller for controlling the action of the chiller let it be understood that I have reference either to the electric switch or to any type of valve which may be used for shutting off and turning on the actuating fluid or fluids of chilling units of refrigerators.

10 On the base 5 is mounted the electric switch 20 which includes the spaced blades 6, the circuit between which is adapted to be closed by the movable blade 9 of the switch lever, which lever is of the Y type and is fulcrumed at 8 on a suitable support 7, it being understood that the blade 9 is suitably insulated from the remainder of the lever and, of course, the terminals 6 of the switch 25 are suitably insulated from each other as is common practice.

15 The Y lever which operates the switch in the embodiment shown in Figure 1, (or which operates the valve in the embodiment shown in Figure 3) consists of two sets of stops or lugs 10 and 11 to be engaged by the long arm 13 of a rocker which is pivoted at 12 to the support 7. 30 When the long arm engages the lower pair of lugs 10 and 11 it will cause the Y lever to turn in one direction, and when it engages the upper pair of lugs 10 and 11 it will cause the Y lever to turn in the opposite direction.

20 The rocker may consist of a U-shaped body having a long arm 13 and a short arm 15 connected by a cross portion 14, the U-shaped body being, as before intimated, pivoted at 12 on the support 7. 16 is a connecting pin carried by the 35 short arm 15 and passing through a slot 38 in the upper end of a push-pull rod 37 hereinafter again referred to.

25 In order that the Y lever may be thrown over by snap action the rocker is moved past its dead center and held there by a spring actuated device consisting of a rod 18 pivoted at 17 to the support 7 and passing through an aperture in the cross member 14, the pivot 17 being so located 40 with relation to the pivot 12 that when the rocker 45

50

has passed its mid-position the spring 19 will function to force it quickly to one or the other of its extremes of movement, see Figures 1 and 3, thereby effecting a quick action of the chiller controller.

20 is a latch which is pivoted at 21 and is continuously pulled in one direction by a suitable spring 22, the latch having a heel 23 to engage the upper end of the latch releasing pin 28.

10 24 is a bellows support which is held suspended beneath the base 5 by suitable bolts 25. On the base 24 is mounted the latch releasing bellows 26 which is provided with a cap 27 to which the release pin 28 is secured, the release pin 28 passing through a threaded bushing 29 having a nut portion 30 by which it may be turned and having a flanged plate or spring cap 31 between which and the cap 27 the bellows spring 32 is located. By changing the spring 32 to one of greater 20 or lesser tension the bellows 26 may be made to operate at different temperature extremes.

33 is a duct communicating with the bellows 26 and with the thermos bulb 3 whereby the action of the bellows 26 is correlated to the action 25 of the bulb 3. 34 represents the rocker actuating bellows, this bellows being similar in construction to the bellows 26 and having a cap 35 into which the push-pull rod 37 is screwed. The rod 37 passes through a threaded bushing 39 having a nut portion 40 by which it may be adjusted and having a spring cap 41 beneath which the bellows spring is located. By changing the spring 42 to one of greater or lesser tension, operation of the bellows at different temperatures may be 35 obtained.

In the Figure 3 modification 43 designates the valve (when a valved type controller is used) the stem 45 of which carries the Y lever 46 which has the stop lugs 47 and 48 corresponding to 10 40 and 11 of the first embodiment of the invention.

Pipes 44 in the energy or fuel line of a refrigerator lead to and from the valve 43.

In operation the thermos bulb 3 is placed in contact with the wall of the chiller preferably 45 beneath the same, where it is at the coldest place, and the thermos bulb 4 is placed at a variable distance from the wall of the chiller 1 depending upon how thick a coating of frost it is desired 50 to permit to form before the bulb 4 acts on its bellows 34.

In Figure 5 I have shown how my switch is connected in series with the normal control switch 53 of the refrigerating system, which system comprises, generally, a chiller 1, a motor 48, compressor 50, condenser 51, high side float 52, and pressurestat or normal control 53. As the refrigerating system per se may be of any well-known type, further description thereof is thought to be unnecessary.

60 Assume the parts to be in position as shown in Figure 1 where the defrosting action is taking place. Frost having formed on the chiller 1 to a sufficient thickness to bridge the space between the wall of the chiller and the thermos 65 bulb 4, causes that bulb to become chilled which contacts the fluid in the bulb 4, duct 38 and bellows 34, thereby effecting a compression of the bellows and a pulling down on rod 37 which rocks the rocker member with its long arm 13 downwardly and forces the Y lever to the full line position shown in Figure 1 to open the electric 70 circuit between the terminals 6. As the rocker is moved to the position shown in Figure 1 the spring 22 will bring the latch 20 beneath the cross 75 portion 14 of the rocker and latch it in its rocked

position. As soon as the frost melts on the chiller and clears from the thermos bulb 4, that bulb will warm up again, thereby expanding the bellows 34 and pushing up on the rod 37.

The movement of the bellows, however, does not become effective on lever 13, while the latch is in the position shown in Figure 1. It is to be understood that normally the fluid in the thermos bulb 3, duct 38 and bellows 26 is contracted and the pin 28 is held down. As soon, however, as the defrosting operation has become completed and the chiller warms slightly as it does when the front is off, the fluid in the bulb 3, duct 38 and bellows 26 will expand, thereby causing the pin 28 to push upwardly against the heel 23 and release the latch 20 from the rocker, thereby permitting the upward movement of the push-rod 37 to move the rocker upwardly to the position shown in Figure 3. As soon as the rocker passes its horizontal or dead center position it will snap over due to the action of the spring 19 and quickly close the circuit at 6.

The operation of the embodiment shown in Figures 3 and 4 is substantially the same as that shown in Figure 1 with the exception that on the downward movement of the rod 37 the valve 43 is closed and circulation of fluid through the chiller stopped, and on the upward movement of the rod 37 the valve is again opened to re-establish the action of the chiller.

By using springs 32 and 42 of various thicknesses the device may be made to operate at various temperatures of the chiller, thus giving the benefit of a temperature adjustment as well as a frost thickness adjustment.

From the foregoing description, taken in connection with the accompanying drawings, it is thought the complete construction, operation, and advantages of my invention will be clear to those skilled in the art to which it relates.

What I claim is:

1. In mechanical refrigerators having a chiller and a controller for shutting off or turning on the chiller; means governed by frost on the chiller for actuating said controller for stopping the action of the chiller for defrosting purposes and for turning it on again when defrosting has been completed, said means comprising a thermostatic bulb lying a distance from the chiller equal to the frost thickness it is desired to accumulate on the chiller, a bellows cooperatively connected with said bulb, said bulb, bellows and their connection containing an expandable fluid, a rocker for actuating said controller, means connecting said bellows and said rocker to cause the controller to stop the action of the chiller during defrosting, a latch to hold said rocker in the stop position, and a second thermostatic bulb and bellows and expandable fluid contained therein to operate with said chiller and with said latch for releasing the latch when the chiller has been defrosted.

2. In mechanical refrigerators having a chiller and a controller for shutting off or turning on the chiller; means governed by frost on the chiller for actuating said controller for stopping the action of the chiller for defrosting purposes and for turning it on again when defrosting has been completed, said means comprising a thermostatic bulb lying a distance from the chiller equal to the frost thickness it is desired to accumulate on the chiller, a bellows cooperatively connected with said bulb, said bulb, bellows and their connection containing an expandable fluid, a rocker

for actuating said controller, means connecting said bellows and said rocker to cause the controller to stop the action of the chiller during defrosting, a latch to hold said rocker in the stop position, 5 and a second thermostatic bulb and bellows and expansible fluid contained therein to cooperate with said chiller and with said latch for releasing the latch when the chiller has been defrosted, and means to vary the action of the thermostatic 10 means for temperature adjustment.

3. In combination with a chiller, means to stop the action of the chiller for defrosting purposes and for restoring the action of the same when defrosting shall have been completed, said means 15 including a thermostat for effecting the stopping action when the frost on the chiller shall have reached a predetermined thickness, and another thermostat to start the action of the chiller when the frost on the chiller shall have melted off.

20 4. In combination, a refrigerating unit, a main thermostat connected with said unit in a position to be constantly acted upon by the temperature thereof, an auxiliary thermostat located exteriorly

of said unit in position to be acted upon when frost accumulates upon said unit to a predetermined extent, conductors forming an electric circuit, electric refrigerating means for said unit operated by the current from said conductors, and circuit opening and closing means for said conductors, said means being jointly controlled by said thermostats to maintain a predetermined frosting condition of said unit.

5. In a refrigerator having a chiller, a refrigerating means for operating said chiller including a normal means of control, of an auxiliary means to stop the action of the chiller for defrosting purposes and for restoring the action of the same when defrosting shall have been completed, said 15 auxiliary means including a thermostat for effecting the stopping action when the frost on the chiller shall have reached a predetermined thickness, and another thermostat to start the action 20 of the chiller when the frost on the chiller shall have melted off.

CHARLES CHRISTIAN HUNDEMER.
